UNITED STATES PATENT OFFICE.

PATRICK J. HARRIGAN, OF CHICAGO, ILLINOIS.

RAILROAD TIE.

Application filed May 5, 1923. Serial No. 636,803.

To all whom it may concern:

Be it known that I, PATRICK J. HARRIGAN, a citizen of the United States, residing at Chicago, in the county of Cook and State of Illinois, have invented new and useful Improvements in Railroad Ties, of which the following is a specification.

This invention relates to improvements in railroad ties and more particularly to a metallic tie in combination with means for securing the rails thereon.

It is an object of this invention to provide a metallic tie for light weight rails such as are used in narrow gauge railroads of the character employed in making surface excavations, in mines and other temporary and permanent uses. It is a further object to provide such a tie with rail locking or securing means co-operating therewith which will firmly secure the rails the desired distance apart and prevent their spreading thereafter. It is also an object of this invention to provide a rail securing means which may be readily tightened by the track inspector without the use of special tools.

The advantages of this invention are numerous. The tie is a strip of light weight metal that is turned back upon itself along each side, imparting additional strength and rigidity, and can be formed continuously and cut into the desired lengths. The tie can be adapted to secure the rails thereon at whatever spacing desired and when the rails are so secured, the securing means may be readily tightened should any of them become loose by the travel of cars upon the rails. Furthermore, the rail securing means may be detached from engagement with the tie should it be desired to remove the rail or change the adjustment with but little difficulty and without the necessity of special tools.

With these and other objects in view, reference is made to the accompanying sheet of drawing, on which like reference characters refer to like parts, illustrating the preferred forms of this invention, yet it is to be understood that minor detail changes may be made without departing from the scope thereof.

In the drawings:

Figure 1 is a view in side elevation of one form of this invention, with parts broken away and partly in section.

Figure 2 is a top plan view of Figure 1.

Figure 3 is a view similar to Figure 1 of a modified form of this invention.

Figure 4 is a top plan view of Figure 3.

In both forms illustrated the tie 1 comprises a strip of light weight metal slightly longer than the distance between outer edges of the flanges of the rails when in their desired position. The side edges throughout their length are flanged upwards and then uniformly bent over towards each other until parallel to the main body of the tie. This flanging and bending the sides of the tie adds greatly to its strength and rigidity. The rails are supported upon the bent over portion 2 of the side flanges of the tie.

In Figures 1 and 2, the outward movement of the rails is limited by cutting the flanged sides 2 of the tie along the bend and then turning the metal of the separated flat portions 3 back towards the center of the tie to engage the outer flanges of the rails 4 on each end of the tie and thereby limit their outward movement. To secure the rails in this position two metallic lock members 5 are inserted, before the rails are placed in position, between the turned over sides 2 of the tie. Each of these members 5 is rectangular in shape and of sufficient width to enter under the bent over sides and slide over the main body of the tie. Each member is cut on each side of the center line in the direction away from the rail they are to engage and the central portion 6 between the cuts is struck up at an angle to project between and above the bent over sides 2 to engage the upper surface of the inner edges of the bottom flanges of the respective rails. The top surface of each lock member under the bent over sides 2 is saw toothed, roughened or knurled.

The lock members are arranged at a distance from the rail stops 3 at the ends of the tie, the rails are placed upon the tie and moved outward to engage the end stops, the lock members are moved over towards the rails, by hand or by a hammer, and when they engage the inner edges of the rail flanges and hold the outer edges of said flanges in engagement with end stops, the flat bent over side portion 2 of the tie on each side is given several blows with a hammer to force the under surface thereof into contact and engagement with the upper saw toothed, roughened or knurled surface of the lock member, as shown at 7, and thereby

prevent movement of the lock members and the rails are securely fastened in place. Should the lock members become disengaged from the tie, a few blows from a hammer 5 upon the upper surfaces of the bent over sides will again cause their engagement with the tie. To detach the lock members, the bent over sides of the tie are raised from engagement by inserting a chisel or other 10 wedge between the upper surface of the lock member and the bent over sides of the tie along the points of contact therebetween and forcing the chisel or wedge therebetween by blows from a hammer.

15 The form illustrated in Figures 3 and 4 differs in that outer lock members 8 are employed in place of the integral end stops 3 on the tie. In this form the inner lock members 5 are of the same construction and 20 operation as the ones above described. The outer lock members 8 are of the same general construction being of rectangular form adapted to slide over the main body of the tie under the bent over sides. In this case 25 each one is cut on each side of the center line on the ends furthest away from each other and the central portion 9 between the cuts struck up at an angle to project between and above the bent over sides and they are 30 bent back upon themselves to engage the upper surfaces of the outer edges of the rail flanges, as shown. In this type of lock member each is preferably formed with a central tongue 10 extending beyond the inner end which is of sufficient width and 35 length to enter between the side members of the inner locking members 5 on each side of the struck up rail flange engaging portion to align the rail engaging portions of 40 each locking member on each side of the rail.

In this form the rails are laid upon the tie the desired distance apart and the inner locking members moved to engage therewith, and the outer locking members are inserted on the tie, if not already there, and moved into engagement with the outer flanges of the rail and both are secured in locked position by blows of a hammer upon 45 the bent over sides of the tie on each side of the rail forcing the sides in engagement with the upper roughened surfaces of the locking members 5 and 8, as at 7 and 11. Both locking members may be disengaged 50 from the tie, as above described in connection with the other form, and the spacing of the rails changed, if desired. Rails of different widths have base flanges of different widths and by providing both locking members for each rail, adjustable, various types 55 of rails are readily secured in place and at any desired distance apart for different gauge tracks as well as on switch ties where additional locking members are provided

for the additional switch rails. If either 65 of the locking members should become loosened from any cause they may be readily secured again by the use of a hammer. If desired in this form both locking members for each rail may be inserted upon the tie 70 and then the bent over sides of the tie at each end crimped or bent towards each other so that the tie and locking members may be transported as a complete unit ready to receive and secure the rails. 75

What I claim is:

1. A metallic railroad tie having bent over side portions with rail engaging stops at each end and inner rail locking members 80 slidably mounted upon the tie under the bent over portions, said bent over portions adapted to be engaged with and secure said locking members upon the tie.

2. A metallic railroad tie having bent over side portions, rail engaging stops adjacent each end of the tie, rail locking members 85 therebetween slidably mounted upon the tie under the bent over sides having a roughened upper surface adapted to be engaged by the bent over portions and secure the said 90 members against movement upon the tie.

3. A metallic railroad tie having bent over side portions throughout its length, rail locking members arranged in pairs for each 95 rail slidably mounted upon the tie under the bent over side portions, each locking member having a struck up tongue extending between and above the bent over side portions adapted to engage the bare flanges of the rails, said bent over side portions adapted to be forced into engagement with said locking members and secure them to the tie. 100

4. A metallic railroad tie having bent over side portions throughout its length, rail locking members arranged in pairs slidably mounted between the body of the tie and bent over portions, each pair of locking members having struck up tongues adapted 110 to engage the opposite edges of the base flange of a rail and each pair of locking members provided with means aligning the tongues on opposite sides of a rail, said bent over side portions adapted to be forced into engagement with the locking members and secure them to the tie. 115

5. A metallic railroad tie having bent over side portions throughout its length and a plurality of pairs of locking members for 120 securing a plurality of rails to the tie, slidably mounted under the bent over side portions of the tie, each locking member having a struck up portion between the bent over sides of the tie adapted to engage a base flange of a rail and portions extending under said bent over sides and adapted to be secured to the tie by forcing the said bent over side into engagement therewith. 125

PATRICK J. HARRIGAN.
